UNITED STATES PATENT OFFICE.

JOHN B. BOLTON, OF PHILADELPHIA, PENNSYLVANIA, ASSIGNOR TO SHAWMUT ENGINEERING COMPANY, OF BOSTON, MASSACHUSETTS, A CORPORATION OF MASSACHUSETTS.

YARN CLAMP.

Application filed September 16, 1926. Serial No. 135,751.

This invention relates to the clamping of the ends of yarn elements wound on spools or beams in proper spaced relation to permit the threading of the different yarn elements into 5 tube frames or other yarn-presenting elements used in weaving or in operations associated therewith, and is intended to provide a simple and reliable construction by which the danger of the yarn elements becoming released and 10 intermingled is reduced to a minimum.

Heretofore yarn clamps for such purposes, comprising a transversely slotted comb and a trough-like covering for retaining the yarn-elements in the slots between the teeth and 15 the comb, have been provided with resilient or spring metal hooks at their opposite ends, as described in the United States patent to Lea 1,153,870, which hooks had to be sprung to one side to permit the cover or yarn-keeper 20 to be applied to the comb and which then were supposed to spring back to place behind the cover to prevent its accidental withdrawal. In practice, however, it often happens that 25 these hooks become sprung from correct position in alignment with the back of the cover and thus allow the cover to drop off from the clamp in the handling or transportation of the yarn-spool with the result that the yarn elements become intermingled with 30 one another so that, before they could be threaded into the tube frame or other yarn-presenting device for weaving, the ends must be carefully separated by hand and restored to their proper positions in the clamping 35 comb.

To avoid such loss and trouble I have devised a construction of yarn-clamp that is not subject to this difficulty and which consists essentially in the combination of a transversely slotted comb and its teeth-embracing cover with retaining elements or latches which are held positively in correct locking alignment or position with relation to the applied cover, one of which is readily movable to releasing 40 position to permit the removal of the cover. These and other features of the invention will be particularly described in this specification and will be defined in the claims hereto annexed.

45 In the accompanying drawings I have illustrated a simple and convenient form of construction and arrangement embodying the principles of this invention, in which:

50 Figure 1 is a perspective view of the assembled comb and cover forming the yarn-

clamp and the interlocking means by which the accidental removal of the cover from the comb is prevented.

Figure 2 is an end elevation of yarn-carrying spool to which is applied my improved 60 form of yarn-clamp.

Figure 3 is a front elevation or edgewise view of the yarn-clamp.

Figure 4 is a plan view thereof with the uppermost portions of the comb and of the 65 cover being broken away to show more clearly the position of the locking latches or elements in correct locking position.

Figure 5 is a detail view showing one of the latches in open or releasing position to 70 permit withdrawal of the comb.

Figure 6 is a detail view through the clamp and one of the locking latches.

In the practice of the invention, according to the form thereof illustrated in the drawings, the comb-bar 1, is of usual construction being transversely slotted on its front side to form yarn-separating teeth 2 for separating the individual yarn elements *a*, and having its rear edge at 1^a reversely turned or 80 folded upon itself to make a longitudinal stiffening channel.

The cover 3 is preferably in the form of a longitudinal trough of approximately U-shape cross section of sufficient depth and 85 width to embrace the forward ends of the teeth 2, when it is applied to the comb. The back or closed end of the trough, however, is formed, near each end thereof, with a latch-receiving recess or notch 3^a.

As usual, the cover is somewhat shorter than the comb-bar and at the ends of said cover are mounted cover-retaining members 4, 5. In this case, instead of riveting these cover-retaining members to the comb, as has heretofore been done, one retaining member is mounted upon a pivot 4^a, carried by the comb. Moreover, the forward end of the latch or retaining member is made in the form of a hook whose tip 4^b is arranged to enter the recess 100 3^a in the cover so as to project somewhat into said recess. The other member 5 may be riveted on the bar.

It will be seen that, by reason of the penetration of the latch into the latch-receiving 105 recess of the cover after the cover is applied to the comb, the latch is positively interlocked with the cover so that it is prevented from being sprung laterally out of locking alignment with the cover. Moreover, since the release 110

2
of the latch with this construction does not require that the latch be made of resilient material, the latch may be made comparatively stiff or rigid, thus further obviating the 5 danger of being sprung out of alignment. The positive engagement between the latch and the recess of the cover also positively prevents accidental endwise displacement as will be explained later.

10 To retain the latch in locking position, while permitting its release for withdrawal of the cover, I employ a suitable actuating spring, in this case a torsional wire spring 6, preferably coiled around the pivot post 4^a, 15 and having one end 6^a hooked into a hole or notch in the latch, while the other end 6^b thrusts against the back 1^a of the comb. As shown in Figures 4 and 5, the latch is preferably formed with a heel or projecting portion 4^c to act as a stop arranged to abut against the back 1^a of the comb to limit the rotative movement of the latch under the pressure of its actuating spring. As the rotative movement in that direction is limited 20 when the latch is in locking position it will be seen that the interlocking engagement of the latch with the recess in the cover positively prevents endwise displacement of the cover on the comb, for although the latch can 25 be moved outwardly by endwise thrust of the cover in its direction, this involved an opposite or inward thrust simultaneously on the other latch and this is positively prevented by engagement of the heel of the other latch 30 against the back of the comb even if the rivet 35 5^a should be loose.

Furthermore the heel 4^c, by limiting the movement of the self-closing latch, facilitates the easy application of the cover to the comb 40 since it may hold the latch at a slight distance from the opposing teeth and thus allow the operative to insert one end of the cover between the latch and the comb by an endwise movement so that only the other latch 45 requires manipulation when applying the cover.

To secure precise alignment between the tip of the latch and the middle line of the back of the cover the tip may be slightly offset laterally from the main body of the latch 50 at any convenient point as at 4^d.

The clamp is attached to the spool in any convenient manner by means of distensible attaching members 10 arranged to be looped over the journals 9 of the yarn-spool or otherwise. The outer corner of the latch may be turned up as at 4^e to clear the spring 10 and also afford a hold for the finger when releasing the latch.

60 In the drawings I have shown only one of the hooks or latches pivoted and spring-actuated since such a construction is obviously not necessary for both of them, as the corresponding end of the cover may be easily 65 inserted so as to engage the fixed latch or

hook 5 in its receiving recess in the cover, if such end be first inserted between the tip of latch 5 and the comb, before the other end of the cover is pushed over the comb.

What I claim is:

1. A yarn clamp for a yarn spool embracing in its construction a longitudinal transversely slotted comb element, a trough-like cover having recesses in its end portions and adapted to embrace the ends of the comb 70 teeth, cover-retaining members mounted on the comb adapted to interlockingly penetrate said recesses to prevent their lateral disalignment with the cover, one of them being releasably held in such interlocked relation by an 75 engaging spring.

2. A yarn clamp for a yarn spool embracing in combination a longitudinal transversely slotted comb, a longitudinal cover 80 provided at its opposite ends with recesses intermediate of its sides, retaining members 85 mounted on the end portions of the comb in position to be interlockingly engaged in said recesses, one of said members being movable out of its receiving recess, and a spring for 90 normally retaining said movable member in locking position in said receiving recess.

3. In a yarn-spacing and holding clamp, the combination of a transversely slotted 95 yarn-receiving comb, a yarn-retaining cover adapted to be applied to the comb teeth to close the slots between them, cover-retaining members one of which is mounted to move in substantially the plane of the cover into position to hold it against removal, said retaining members being held positively against 100 displacement from the plane of the cover when in locking position.

4. In a yarn clamp the combination of a transversely slotted comb for retaining the 105 yarn elements in spaced relation, a slot closing cover adapted to embrace the comb teeth and provided with latch-receiving recesses, latches adapted to lock the cover against removal from the comb, said latches having 110 interlocking engagement with said recesses in the cover to maintain them against lateral disalignment with the cover, when in locking position.

5. In a yarn clamp the combination with a 115 transversely slotted comb, and its cooperating cover, means for locking said cover releasably on the comb, said locking means having movement only in the plane of the cover to permit release of the cover from the comb, 120 and being permanently secured to the comb.

6. In a yarn-clamp the combination with a transversely slotted comb and its yarn-confining cover, of a self-closing latch arranged to move to and from locking position in the 125 plane of the assembled cover by pivotal connection with the comb.

7. In a yarn-clamp for yarn spools, the combination with a transversely slotted comb and its yarn-confining cover, spring-closed 130

latches pivotally mounted on the ends of the comb to interlock with the cover when applied to the comb, and means for limiting the spring-actuated movement of the latches to prevent them from pressing against the teeth of the comb.

8. A yarn clamp for a yarn spool embracing in its construction a transversely slotted comb element, a trough-like cover adapted to embrace the ends of the comb teeth, cover retaining means and cooperating anchoring means comprising mutually facing hooks at-

tached respectively to the end portions of the comb to project inwardly into overlapping engagement with the respective ends of the cover, one of said hooks being movable outwardly beyond the adjacent end of the cover and means for normally maintaining the movable hook in its inward overlapped relation to the cover.

In witness whereof, I have subscribed the above specification.

JOHN B. BOLTON.
